COMBINED TELEVISION, RADIO, AND BAR

George J. Fischer, St. Louis, Mo., assignor to Fischer Electronics, Inc., St. Louis, Mo., a corporation of Missouri

Filed May 9, 1960, Ser. No. 60,509

Term of patent 3½ years

(Cl. D33—19)

FIGURE 1 is a front perspective view of a combined television, radio and bar showing my new design; and FIGURE 2 is a rear view thereof.

The side of the article not shown is the same as that shown while the top of the television cabinet is plain and unornamented.

I claim:

The ornamental design for a combined television, radio and bar, substantially as shown and described.
